UNITED STATES PATENT OFFICE.

THOMAS RHODUS, OF CHICAGO, ILLINOIS.

ELECTRICAL SWITCH.

Application filed April 30, 1924. Serial No. 709,967.

This invention relates more particularly to that type of electrical switches in which means are provided for obtaining a rapid or snap movement between the contact parts in making and breaking an electric circuit in which it is arranged, and the present improvement has for its object:—

To provide a structural formation and combination of parts and mechanisms whereby the usual rapid or snap movement of the movable contact blade is effectively attained and by means of which a sliding surface cleaning contact movement between the movable and fixed contact plates or members, in angular relation to the path in which the contact end of the movable contact blade moves in making and breaking contact, is simultaneously attained when making contact in a simple and effective manner, all as will hereinafter more fully appear.

In the accompanying drawing:

Figs. 1 and 2 are companion top views, with parts in section, showing the present switch mechanism, the open and the closed conditions thereof.

Figs. 3 and 4 are like companion side elevations of the same, with the supporting base shown in section.

Fig. 5 is a top view of a modification, in which the operating pin or stud of the mechanism has rectilinear reciprocating movement in place of the rotary reciprocating movement illustrated in Figs. 1 to 4, inclusive.

Like reference numerals indicate like parts in the several views.

In the construction shown in the drawing, as illustrative of the present improvement, the supporting base 1 may constitute a portion of an enclosing shell, casing or other part of a stationary member of the apparatus to which the switch is applied, and as usual the base 1 provides means for the attachment, in proper insulated relation, of the stationary contact member 2, usually in the form of a pair of resilient contact plates, and of the pivotal support for the rocking contact blade 3 of the switch mechanism. The contact member 2 may be of a rigid form and the resilient contact blades may be carried by the contact blade 3.

In the present improvement the rocking contact blade 3, is preferably of the obtuse angular plate form shown in Figs. 3 and 4, pivoted near its mid-length to the movable end of the hereinafter described rocker link

4, and with its upper edge formed with inclined contact wings 5 and 6 against which a manually actuated operating stud or pin 7 has operative contact, to impart rocking movement to the contact blade 3, in the operation of the mechanism.

The operating stud or pin 7 may be carried as a radially projecting element of an operating spindle 8, the journal bearings of which have fixed relation to the base 1, as shown in Figs. 1 to 4 inclusive. Or the said stud or pin 7 may be carried by a sliding bar 8' adapted for manual reciprocation in guides arranged in fixed relation to the base 1, as illustrated in Fig. 5.

In the present improvement the aforesaid rocker link or bar 4 is pivoted by a pivot 9 at one end in a suitable pivot bracket 9' on the base 1 and at its other end has supporting attachment to the rocking contact blade 3 by a pivot pin 10. With a view to attain effective results stop lugs 11 and 12 are fixed on the bracket 9', at opposite sides of said rocker link 4, to limit the amount of rocking movement of the same in actual use.

With the construction so far described, a switch mechanism is provided which operates wholly through the movement of the operating stud or pin 7 but in a comparatively slow manner with a view to a rapid or snap action of the parts, provisions as follows are made:

A spring 13 is fixed at one end to a post 14 or other usual means on base 1, and at its other end is attached to a lateral stud 15 on the side of the contact blade 3, at a point a distance removed from the point of pivotal connection 10 between said contact blade 3 and its carrying link or rocker 4 aforesaid.

The arrangement is such that in the operation of the present switch mechanism, and with the parts in the open or broken circuit position shown in Fig. 3, with a manual actuation of the operating stud or pin 7 to the right in said view said stud or pin pushes against the contact wing 5 of the movable contact blade 3 and initially effects a rocking movement of said blade and moves its carrying link 4 upon the pivot 9 of said link in the bracket 9' aforesaid, from the position shown in full lines in Fig. 3, to the position shown in dotted lines in said view. The further movement to the right of the operating pin or stud 7 tends to tilt the contact end of the blade 3 downward toward the stationary contact member 2 until one

- end of the spring 13 and the line of stress of said spring are moved downward past the center of said operating stud or pin 7, and after such movement the spring 13 is adapted to exert a tensional strain on the parts and draw or rock the combined contact blade 2 and carrying link 4, back from the position shown in dotted lines in Fig. 3, to that shown in full lines in Fig. 4, and incidentally thereto effects the heretofore described sliding and cleaning contact movement between the movable and stationary contact members 3 and 2 of the switch mechanism. When the said operating pin or stud 7 is moved to the left from the position shown in Fig. 4, into contact with the wing 6 of contact blade 3, further continued movement of said pin 7 to the left restore the parts to the position shown in full lines in Fig. 3.
- 20 In cases where the spring 13 aforesaid, is omitted, or where the spring becomes damaged or inoperative, the continued travel of the operating stud or pin 7, will effect a contact between the said contact members 2 and 3 in a slower manner, by the continued contact movement of said operating stud or pin 7 against the contact wing 5 of the contact blade 3, to the right in Fig. 4, and without the snap action which said spring would effect.

Having thus fully described my invention, what I claim and desire to secure by Letters Patent is:—

1. In an electric switch, the combination 25 of a support, a stationary contact member secured to said support, a movable contact member pivoted on said support in operative relation to said stationary contact member by a rocker link pivoted at one end to the movable member and at the other end to said support, and operating means imparting movement to said rocker link by direct engagement with said movable member.
2. In an electric switch, the combination 45 of a stationary support, a stationary contact member secured to said support, a movable contact member pivoted on said support in operative relation to said stationary contact member by a rocker link pivoted at one end to the movable member and at the other end to said support, a spring connected to said movable member and arranged to exert a tension thereon in a direction across the point of pivotal connection between said member and the rocker link, and means for imparting rocking movements to said movable member by direct engagement therewith.
3. In an electric switch, the combination 60 of a stationary support, a stationary contact member secured to said support, a movable contact member pivoted on said support in operative relation to said stationary contact member by a rocker link pivoted at one end to the movable member and at the other end to said support, and means for impart-

ing rocking movements to the same comprising a pair of inclined wings on the movable contact member and an operating stud moving in operative relation to said wings.

4. In an electric switch, the combination 70 of a stationary support, a stationary contact member secured to said support, a movable contact member pivoted on said support in operative relation to said stationary contact member by a rocker link pivoted at one end to the movable member and at the other end to said support, a spring connected to said movable member and arranged to exert a tension thereon in a direction across the point of pivotal connection between said member and the rocker link, and means for imparting rocking movements to said movable member, the same comprising a pair of inclined wings on the movable contact member and an operating stud moving in operative relation to said wings.

5. In an electric switch the combination of a support, a stationary contact member secured to said support, a movable contact member having associated relation with said stationary contact member, and operating means for imparting a forward and backward movement to said movable member during a movement of the same downward toward said stationary member.

6. In an electric switch, the combination of a support, a stationary contact member secured to said support, a movable contact member adapted to make contact with said stationary contact member, and means for imparting bodily rocking movements to said movable contact member; the said means comprising a cam surface on the movable contact member and an operating stud moving in operative relation to said surface.

7. In an electric switch, the combination of a support, a stationary contact member secured to said support, a movable contact member adapted to make contact with said stationary contact member and held in bodily rocking operative relation to said stationary contact member by a rocker link, an operating stud moving in operative relation to and having a point of contact upon said movable contact member, and a spring arranged to exert a tension upon said movable contact member in a direction across the said point of contact of the said operating stud upon said movable contact member.

8. In an electric switch, the combination of a support, a stationary contact member secured to said support, a movable contact member adapted to make contact with said stationary contact member and held in bodily rocking operative relation to said stationary contact member by a rocker link pivoted near one end to the movable contact member and pivoted near the other end to a support, an operating stud moving in oper-

ative relation to and having a point of contact upon said movable contact member, and a spring arranged to exert a tension upon said movable contact member in a direction across the point of pivotal connection between said movable contact member and said rocker link when the said operating stud is in one position and to exert tension on said

movable contact member in a direction across the point of contact of said operating stud upon said movable contact member when the operating stud is in another position.

Signed at Chicago, Illinois, this 28th day of April 1924.

THOMAS RHODUS.
